Des. 184,657

Patented Mar. 24, 1959

184,657

OVERHEAD LIGHTING WARE LENS

Warren O. Benjamin, Beaver Dams, N.Y., assignor to
Corning Glass Works, Corning, N.Y., a corporation of
New York

Application June 8, 1956, Serial No. 41,815

Term of patent 14 years

(Cl. D48—16)

Fig. 1 is a sectional elevational view of an overhead lighting ware lens embodying my new design taken on line 1—1 of Fig. 2.

Fig. 2 is a bottom plan view thereof.

Fig. 3 is a side elevational view thereof.

I claim:

The ornamental design for an overhead lighting ware lens, as shown.
